UNITED STATES PATENT OFFICE.

GEORGE B. GARDNER, OF HAVERHILL, AND FREDERICK M. FURBER, OF LYNN, MASSACHUSETTS.

HEADLIGHT-HOLDER.

No. 920,860.

Specification of Letters Patent.

Patented May 4, 1909.

Application filed July 31, 1908. Serial No. 446,218.

To all whom it may concern:

Be it known that we, GEORGE B. GARDNER, of Haverhill, and FREDERICK M. FURBER, of Lynn, county of Essex, State of Massachusetts, have invented an Improvement in Headlight-Holders, of which the following is a specification.

This invention relates to an apparatus for supporting a headlight so that it may be 10 swung by suitable means, and has for its object to provide a headlight or lantern holder of simple construction, which may be readily attached to a car without any material change being made in the construction 15 thereof, and which is readily removable so that it may be changed from one end of the car to the other.

For an understanding of the invention, reference is made to the accompanying drawings, in which,

Figure 1 is a front elevation of a section of the dashboard of a car provided with a device made according to our invention. Fig. 2 is a side elevation thereof. Fig. 3 is a sectional view on the line 3—3, of Fig. 2. Fig. 4 is a top plan view of the lantern holder. Fig. 5 is a detail view partly in section on line 5—5, of Fig. 4. Fig. 6 is a detail plan view of the lower lantern-engaging bracket. Fig. 7 is a detail front view of the lower base bracket. Fig. 8 is a central sectional view on line 8—8, of Fig. 4. Fig. 9 is a top view of a portion of the upper base bracket.

The dashboard *a* of the car is provided 35 with the usual hanger bar *b* which is connected thereto at each end and extends parallel therewith at a short distance therefrom.

The headlight or lantern-holding devices 40 illustrated comprise an upper base bracket *c* provided with a pair of hooks *c'* on its rear side, similarly arranged to the hanger hooks on an ordinary car lantern, and adapted to engage the hanger bar *b*, so that said bracket 45 may be hung on the bar *b* in the same manner as the lantern. Said base bracket *c* is provided with a centrally-disposed, forwardly extending projection *c'*, into the under side of which a vertically disposed tube *d* is 50 threaded. Said tube *d* is also threaded at its lower end into a base bracket *e*, said bracket being provided with a pair of depending ears

e', between which a vertical slot is formed adapted to receive a stud *f* fixed in the dashboard *a*. A shaft *g* is journaled in the dashboard *a* and on the floor *a'* of the car in a horizontal position, and the rear end of said shaft is rigidly connected to the middle portion of a transversely disposed treadle *h*, the construction of which is particularly de- 60

scribed in said patent.

An arm *i* is rigidly connected to the front end of the rod *g* closely adjacent the front side of the dashboard and extends vertically when the treadle *h* is in its middle position, 65 that is, when both end portions thereof are elevated to the same extent. An arm *k* is rigidly connected to the arm *i* and extends at right angles thereto and forwardly in an oblique direction, with reference to the front of 70 the car, when the arm *i* is in the vertical position. A rod *m* passes through the tube *d* and base brackets *c* and *e*, and an arm *n* is rigidly connected to the lower end thereof, said arm *n* normally extending forwardly at 75 right angles to the dashboard, and downwardly, as shown in Figs. 2 and 3. A link *o* is pivotally connected to the end of the arm *k*, and is provided with a hook-shaped end portion *o'* which is adapted to pass through 80 an aperture *n'* formed in the front end of the arm *n*.

A lantern bracket *p* is provided with a rearwardly projecting collar piece *p'*, into which the upper end of rod *m* is fitted, said rod being made square at its upper end so 85 that neither can turn with relation to the other, a set screw, or other suitable means for forming a suitable connection therebetween, being provided. Said bracket *p* is provided with flat faced, horizontal arms *p*², which extend in opposite directions from the middle thereof, said arms being provided with forwardly projecting fingers *p*³ at their ends, as shown in Fig. 4. A headlight lantern *q*, of suitable form, having hooks *q'* on its back 95 side, is adapted to be hung upon said arms *p*² between fingers *p*³, as shown in Figs. 1, 2 and 4, said fingers *p*³ being adapted to engage the sides of the lantern to hold the same in position. The upper side of the base *c* is provided with a V-shaped groove *c*², which extends transversely thereof and perpendicularly to the front of the car, the line of the bottom of said groove intersecting the axis of 100

rod m . The under side of the base portion p' of the lantern bracket p is provided with a V-shaped tooth p^4 which is normally adapted to fit closely in the groove c^3 when the under side 5 of said base portion is resting on the upper side of the base bracket e and the parts are in their middle or normal position. A lantern-holding bracket r is swiveled on the tube d and is adapted to rest on the upper side of bracket e , said bracket being provided with horizontal arms r' having forwardly projecting fingers r^2 at their ends adapted to engage the sides of the lantern and hold it from swinging 10 on its hooks q' . A spring s is interposed between the under sides of the bracket e and the arm n , and acts normally to hold the tooth p^4 in the notch c^3 .

The operation is as follows:—When it is desired to direct the rays of light to one side 20 or the other the motorman presses on the corresponding end of the treadle rotating the shaft g in that direction, as for instance if he presses on the left-hand end of the treadle piece h the arm i will be swung to the left 25 swinging the arm n , through arm k and link o , in the same direction. This will cause the rod m to be rotated to the left, which will in turn swing the lantern bracket p , and therefore the lantern, in the same direction, 30 see Fig. 1. This will cause the tooth p^4 to ride up on the corresponding side of the notch c^3 lifting the lantern and rod m slightly and compressing the spring s , as shown in Fig. 5. As soon as the pressure on the 35 treadle is relieved the force of gravity and the spring s will immediately cause the lantern to be returned to its middle position. The same operation takes place when the opposite end of the treadle is depressed, except 40 that the parts will be swung to the right, as will be obvious. By this means the motorman may, without lifting his heel from the floor, and by simply swinging or tilting the fore-part of his foot, with his heel as a pivot, 45 direct the rays of light in either direction, the lantern automatically returning to the middle position when the pressure on either arm of the treadle is relieved. If it is desired to remove the lantern and its supporting means, 50 and to place it on the other end of the car, it is simply necessary to unhook the link o from the arm n and then lift the base bracket c up, so that the hooks c' will be lifted out of engagement with the bar b , and the bracket e 55 will be lifted out of engagement with the stud f . The supporting means for the lantern will then be free of the car so that it may then be placed on the opposite end thereof, which end will be similarly provided with a 60 treadle operated mechanism similar to that already described.

Having thus described our invention, what we claim as new and desire to secure by Letters Patent is:—

1. A headlight-directing holder, comprising a pair of superimposed brackets, means for removably connecting one of said brackets to a support, a tube rigidly connected to said brackets, a rod rotatably mounted in said tube, a headlight holder connected to one end of said rod, and means for oscillating said rod, substantially as described. 65

2. A headlight-directing holder, comprising a pair of superimposed brackets, means for removably connecting one of said brackets to a support, a tube rigidly connected to said brackets, a rod rotatably mounted in said tube, a headlight holder connected to one end of said rod and oscillating means for said rod having a removable connection therewith, substantially as described. 70

3. A headlight-directing holder, comprising a pair of superimposed base brackets having means for removably connecting them to a support, a vertical tube rigidly connecting said brackets, a rod rotatably mounted in said tube, a pair of headlight holders, one rigidly connected to the upper end of said rod and the other swiveled on said tube, and means for oscillating said rod, substantially as described. 85

4. A headlight-directing holder, comprising a pair of superimposed base brackets, means for removably connecting said brackets to a support, a tube rigidly connecting said brackets, a rod rotatably mounted in said tube and extending above and below said brackets, respectively, a headlight-holder rigidly connected to the upper end of said rod and supported by the upper base bracket, and means, removably connected to the lower end of said rod, for oscillating the same, substantially as described. 95

5. A headlight-directing holder, comprising a pair of rigidly connected superimposed base brackets, a rod rotatably mounted in said brackets and extending above the upper bracket and below the lower bracket, a headlight-holder rigidly connected to the upper end of said rod, said upper bracket having a centering recess provided with inclined faces at each side thereof and said holder having a correspondingly shaped depending portion adapted to enter said recess and ride on said inclined faces as the rod is turned in either direction, a collar on the lower end of said rod, a spring interposed between said lower bracket and said collar, and means for oscillating said rod, substantially as described. 110

6. In a headlight-directing and holding apparatus, the combination of a support having a horizontal bar, a pair of rigidly connected superimposed base brackets, one of said brackets having hooks on the rear side thereof adapted to engage said bar and the lower bracket having a vertical slot extending from the lower end thereof, a stud mounted in said support adapted to enter said slot, a rod 125

rotatably mounted in said brackets, a head-light-holder connected to the upper end of said rod above said upper bracket, and means for oscillating said rod removably connected to the lower end thereof below said lower bracket, substantially as described.

In testimony whereof, we have signed our

names to this specification, in the presence of two subscribing witnesses.

GEORGE B. GARDNER,
FREDERICK M. FURBER.
